FREQUENCY DRIFT INDICATOR

Filed Aug. 28, 1941

UNITED STATES PATENT OFFICE

2,349,501

FREQUENCY DRIFT INDICATOR

Alfred Kahn, Hollis, N. Y., assignor to Radio Corporation of America, a corporation of Delaware

Application August 28, 1941, Serial No. 408,633

14 Claims. (Cl. 172—245)

This invention relates to frequency drift indicators and has particular reference to a device for checking the frequency of an alternating current with that of a known standard.

In multiplex telegraph systems, it is common practice to maintain synchronism between local and remote apparatus by means of tuning forks and phase correction devices. Usually, the transmitting station is provided with a tuning fork control for the distributor speed. It is also a common practice to generate an alternating current, the frequency of which is maintained substantially constant by means of a tuning fork. When telegraph signals are transmitted through a multiplex distributor, the speed of which is thus controlled, it is possible, by well-known means, to maintain the speed of a distributor at a receiving station in synchronism with the received signals.

In some of the more extended communications systems, it has been found that a number of different tuning forks are necessary in order to provide all the frequency controls that are necessary. It is desirable to check the frequency of these tuning forks from time to time with an even better standard of frequency. Such a standard is one which is quite costly to build and maintain and, therefore, precautions are taken to operate the standard itself under ideal conditions such as would minimize the frequency drift therein.

It is an object of this invention to provide convenient means for checking certain practically operable frequency control devices with the frequency of a known standard that may be reserved merely for checking purposes.

It is another object of my invention to provide a convenient arrangement for dividing the frequencies from two different sources, each of a different fundamental frequency, so that a comparison may be made between two sub-harmonic frequencies common to the two sources.

Certain features of my invention as herein disclosed are claimed in a divisional application Serial No. 504,114, filed October 2, 1943, and entitled "System for frequency conversion and comparison of frequencies."

In carrying out my invention, I preferably use electronic circuits for deriving the common sub-harmonic frequency. I then compare the sub-harmonics obtained from two different sources by means of a stroboscope. The stroboscope may be of the type which embodies a gaseous glow tube rotating on the shaft of a synchronous motor. The speed of the motor may be determined by the frequency of the alternating current derived from the tuning fork. On the other hand, the

flashing of the glow tube may be made by means of short, sharp impulses derived from a laboratory frequency standard.

My invention will now be described in more detail, reference being made to the accompanying drawing, the sole figure of which represents diagrammatically a typical embodiment.

Referring to the drawing, I show a pair of input terminals 1 on which may be impressed, for example, an alternating current of 480 cycles per second, representing the output from a tuning fork generator the frequency of which is to be compared with that of a laboratory standard.

The 480-cycle frequency is fed across transformer 3 to the input circuit of a discharge tube 5. This tube is self-biased by means of cathode resistor R2, which is shunted by capacitor C1. The input circuit includes a grid resistor R1 and the secondary of transformer 3.

20 A limiter stage comprising discharge tube 7 is controlled by output from tube 5. The control potential is developed across resistor R3 the anode-connected end of which is coupled through capacitor C2 and resistor R5 to the control grid of tube 7. Grid leak resistor R4 is connected to the grounded cathode of tube 7.

The output from tube 7 is a square wave which serves to synchronize a multivibrator comprising discharge tubes 9 and 11. The circuit constants 30 of these tubes are preferably selected to produce a 40-cycle frequency, thus dividing the 480-cycle synchronizing frequency by 12. For tuning the multivibrator the values of resistors R6, R8, R9, R10 and R11, and of capacitors C3 and C4 may 35 be determined empirically. Care should be taken that resistors R10 and R11 are not subject to ohmic variations due to temperature or humidity. The values of capacitors C3 and C4 should also be substantially independent of the temperature 40 and humidity variations. A critical tuning adjustment of the multivibrator is made by fixing the value of resistor R6 so that the multivibrator will keep in step with the twelfth sub-harmonic of the 480-cycle output from tube 7. The anode 45 voltages in tubes 7, 9, and 11 are adjusted by means of resistor R7.

The grid of tube 11 is coupled to the anode of tube 9, and the grid of tube 9 is coupled to the anode of tube 11. This cross-coupling of the input and output electrodes in the two tubes provides the well known multivibrator action which is desired in order to produce a 40-cycle output which is synchronized with the 12th sub-harmonic of the 480-cycle tuning-fork generator.

The square-wave output from tube 11 is applied

across resistor R12 and capacitor C5 to the grid of an amplifier tube 13. This tube is self-biased by means of a cathode resistor R13. The resonant circuit consisting of inductance 15 and capacitor C6 is connected between the grid of tube 13 and ground, thus providing a smoothing action which results in the output from tube 13 of a 40-cycle current of essentially sine-wave formation. This current is further smoothed by means of the inductance of an output transformer 17 and a capacitor C7, the latter being connected between the anode of tube 13 and ground.

The secondary of transformer 17 is connected to input terminals of a power amplifier 18, which may be of a type commonly used to deliver frequency-controlled power to one or more synchronous motors. Such motors are, in turn, used to drive telegraph distributors, and the like. In this case, however, the operation of my invention is best explained by showing output leads from the amplifier 18 connected to a synchronous motor 21, the shaft of which carries a small neon lamp 23. The excitation of this lamp is made intermittent by means of short sharp pulses at a frequency of 20 cycles per second, which corresponds with the nominal shaft rotation speed of the motor 21. The derivation of the pulses for excitation of the lamp 23 will now be explained.

Assuming that a 1000-cycle source is available for reference purposes and that this source is maintained within very close limits of variation, according to laboratory standards, then output energy from such a source will be applied to input terminals 2 and impressed across transformer 4 upon a first stage input circuit of a twin triode discharge tube 6. This input circuit is tuned by a capacitor C8 in shunt with the secondary of transformer 4. Resistor R15 also forms part of the same input circuit.

The first and second discharge zones of tube 6 are controlled respectively by grids a and b. The output circuits of the first and second zones are cascaded. Grid b is in circuit with resistor R17 and with the secondary of transformer 8. The primary of this transformer is tuned by capacitor C10 and is fed with an alternating potential developed across resistor R16 which is disposed in the output circuit of the first discharge zone in tube 6. Capacitor C9 isolates the direct current anode potential in the first discharge zone of tube 6 from the grounded primary of transformer 8.

Discharge tube 10 has input and output circuits which are similar to those of tube 1. Its input circuit includes resistors R19 and R20, and the junction between these resistors is coupled across capacitor C11 to the anode of the second discharge zone in tube 6. A load resistor R18 is provided in the output circuit of this discharge zone. The output circuit of tube 10 includes resistor R21 across which potentials are developed suitable for controlling the frequency of a multivibrator, the latter comprising discharge tubes 12 and 14. The combined action of tubes 6 and 10 is that of amplification and limiting, and the product is a 1000 cycle square wave.

The circuit components for the multivibrator tubes 12 and 14 are similar to those of tubes 9 and 11 except for certain constants which are chosen to produce frequency division by 10 of the 1000-cycle synchronizing frequency. The operation of this multivibrator will, therefore, be understood without further description, except to point out that the values of resistors R25 and R27 are suitably differentiated for the purpose

of providing such compensation for unbalance as will cause the multivibrator to be maintained in step with an even sub-harmonic (the tenth) of the 1000-cycle control frequency. Resistor R22 determines the anode potentials applied in tubes 10, 12 and 14.

Output impulses from the multivibrator described in the preceding paragraph are fed through capacitor C14 and resistor R28 to the input circuit of a succeeding stage comprising a gaseous discharge tube 16. To ignite this tube, such impulses are applied negatively to the cathode. The control grid is connected to the cathode through resistors R29 and R31, the junction between these two resistors being grounded. Anode potential is supplied to the tube from a direct current source 18 through resistor R34. In order to adjust the ignition and extinction potentials, resistor R31 is constituted as a variable potentiometer, the movable tap on which is connected to one end of resistor R33 for feeding a suitable positive potential thereto with respect to ground. An appreciable time is required for capacitor C15 to be charged through resistor R34. During this time, the anode potential in tube 16 builds up gradually to a value such that the next succeeding negative impulse applied to the cathode will produce an ionization discharge. This charge, however, is of only momentary duration since the sudden discharge of capacitor C15 again reduces the anode potential to a value below that which will sustain ionization. The short sharp discharges in tube 16 result in the delivery of momentary excitation potentials to a neon lamp 23 used for purposes of indicating the frequency drift.

The values of resistor R34 and capacitor C15 are so determined, therefore, that the tube 16 acts as a frequency divider and its periodicity is preferably such as to divide the control impulses by 5, thus producing an output of 20 cycles per second, whereas the output from the multivibrator tubes 12, 14 was stated to be 100 cycles per second.

One electrode of the lamp 23 is connected through a collector ring and brush and through resistor R30 to the cathode of tube 16, and the other electrode of the lamp 23 is grounded.

The lamp 23 constitutes an indicating element for a stroboscope, other portions of which include a stationary translucent disc 22 on which there appears a circular scale suitably divided for observing the angle of drift of the neon lamp flashes within a given period of time. The lamp 23 is mounted for rotation on the shaft of motor 21. The flashes appear through the translucent disc 22. The disc 22 may be graduated in degrees, or as an alternative, may be graduated in terms of percentage deviation of the frequency of the tuning fork source with respect to a corresponding fixed standard of the same frequency.

It will be clear from the above description that the flashing of the lamp 23 once per revolution around the scale of the disc 22 can be observed as an indication of frequency drift with respect to the 480-cycle fork frequency in relation to the 1,000-cycle laboratory standard.

The motor 21 is mounted on a chassis behind a stationary calibrated translucent disc 22. A neon lamp 23 mounted on the motor shaft is excited by pulses generated from the 1,000-cycle standard and is viewed through the aforementioned disc, which may be calibrated in degrees. With the motor operating at a shaft speed of 20 R. P. S. and the neon lamp flashing once per

revolution, a convenient means is thus afforded for reading fork generator accuracy directly from the calibrated dial 22. Furthermore, a short time observation will indicate to the operator whether the working standard is slow or fast and to what degree. The change in fork speed caused by adjustment can be observed immediately so that a more accurate setting can be made in a brief space of time. The last statement refers to normal operating adjustments made by means of a fork drive potentiometer (not shown) and does not, of course, include major thermostat readjustments which may be found necessary from time to time.

The advantages to be derived from my improved frequency drift indicator will be better understood from the following discussion of the theory of operation.

By observing the amount of drift in degrees for a given period of time, the speed difference in parts in 100,000 can be readily determined. For example, in one second, the motor rotation is 20 revolutions, during which time the neon lamp 23 sweeps through 7200 degrees, provided the fork generator frequency is exactly what it should be. The relation between x degrees of drift per second and the frequency error in parts per 100,000 is shown by the equation—

$$\frac{x}{7200} = \frac{1}{100,000}$$

or $x = .072^\circ$ per part in 100,000 cycles per second.

Thus a shift of $.072^\circ$ per second is equivalent to an accuracy of one part in 100,000. Because of the difficulty of reading so small an angle, it is preferable to check for 100 seconds, during which the drift would be 7.2° per part in 100,000.

If R is the observed difference in degrees in 100 seconds, then the frequency drift may be expressed as

$$\frac{R}{7.2} = \text{parts in 100,000}$$

It is perhaps preferable to divide the circumference of the scale on the disc 22 into 50 divisions. Each division will then be 7.2° , so that the frequency drift in parts in 100,000 will correspond with the number of scale divisions through which the neon flash drifts in 100 seconds.

The operator by observing the direction of drift of the neon flash can tell whether the 480-cycle fork generator is slow or fast. If the drift is clockwise, this standard is fast; if counter-clockwise, it is slow.

The foregoing description may suggest modifications of my invention, particularly to those skilled in the art, but such modifications should be considered comprehended within the scope of the invention itself.

I claim:

1. A synchronism indicator for comparing the frequency of a local alternating current source with that of a predetermined standard frequency source, comprising electronic circuits for dividing the frequencies of the two sources by different factors, a motor synchronously driven by an amplified current which is a sub-harmonic of the frequency of said local source, a lamp of the gaseous discharge type mounted for rotation on the shaft of said motor, and means for exciting said lamp by short sharp impulses substantially once per revolution of said motor shaft, said impulses being derived from the frequency dividing

circuit appropriate to said standard frequency source.

2. An indicator according to claim 1 and including a circular scale mounted coaxially with respect to the lamp's orbit and in a plane parallel thereto.

3. An indicator according to claim 1 wherein said electronic circuits include multivibrators, each tuned to a subharmonic of the control frequency applied thereto.

4. The method of indicating frequency drift in an alternating current generator, which comprises deriving a sub-harmonic of the alternating current output from said generator, deriving a different sub-harmonic of a predetermined reference frequency, producing a rotative indication under synchronous control of the first said sub-harmonic, producing intermittent flashes under synchronous control of the second said sub-harmonic, and causing said flashes to be oriented by said rotative indication.

5. Apparatus for indicating frequency drift in an alternating current generator, comprising frequency dividing means for deriving a sub-harmonic of the output from said generator, a power amplifier under control of the sub-harmonic derivative, a standard frequency source, means for deriving a sub-harmonic of the output from said source the frequency of which is comparable with that of the first said harmonic, a synchronous

motor connected for operation by output energy from said power amplifier, a lamp of the gaseous discharge type mounted for rotation on the shaft of said motor, an impulse generator synchronized by a second sub-harmonic derivative from said standard frequency source, and means including slip-ring connections between said impulse generator and said lamp for causing said lamp to produce a stroboscopic indication.

6. Apparatus according to claim 5 wherein said impulse generator includes a grid-controlled gaseous discharge tube and means including a time-constant device in the output circuit of said discharge tube for quickly interrupting the discharge therein by reduction of the anode voltage to a value below the discharge extinction level.

7. In a frequency drift indicator for comparing the frequency of an oscillation generator with that of a predetermined standard frequency source, separate amplifier-limiter circuits connected one to said generator and the other to said source, said circuits being arranged to deliver substantially square wave outputs at the respective frequencies of said generator and said source, two frequency divider circuits each connected to receive and be controlled by one of said square wave outputs respectively, a rotatable luminous device, means including a gaseous discharge tube for pulsatively connecting said luminous device to the output side of one of said frequency divider circuits, and means synchronized by the output from the other of said frequency divider circuits for maintaining rotation of said luminous device.

8. The combination according to claim 7 wherein said gaseous discharge tube is arranged to further sub-divide the output frequency of the frequency divider circuit to which it is connected, and to deliver short sharp pulses to said luminous device at a rate commensurate with the revolutions of said device.

9. The combination according to claim 7 wherein said frequency divider circuits are constituted as multivibrators tuned to a desired sub-harmonic of the input frequency applied thereto.

10. The combination according to claim 7 wherein said gaseous tube is in circuit with a time constant means for periodically building up a discharge potential in the output circuit thereof, said time constant means being arranged to limit each discharge period to a small fraction of the extinction period.

11. The combination according to claim 13 in which said gaseous discharge tube means is provided with circuit parameters the time constant value of which causes the discharge frequency to be a submultiple of the control frequency delivered thereto.

12. In a frequency drift indicator, a standard frequency source, an oscillation generator the normal frequency of which bears a harmonic relation to a submultiple frequency derived from said source, means for producing two separate square wave outputs, said means comprising one unit connected to said source and another unit connected to said generator for independent control thereby, two multivibrator circuits each connected to an appropriate one of said square wave producing means for control thereby, each multivibrator circuit being operative as a frequency divider, a gaseous discharge tube having an input circuit controlled by output energy from one of said multivibrators, a time constant device for reducing the frequency of discharge pulses in said gaseous tube to a sub-harmonic of the control frequency applied to its input circuit, a lamp of the gaseous discharge type mounted for rotation in an indicating orbit, said lamp being con-

nected in shunt with a cathode resistor appropriate to said gaseous discharge tube, and motor means synchronously driven by amplified output energy from the other of said multivibrators for causing said lamp to rotate in its orbit at a speed suitable for producing a stroboscopic effect.

13. In a frequency drift indicator, a standard frequency source, an oscillation generator the normal frequency of which bears a harmonic relation to a submultiple frequency derived from said source, two separate wave shaping circuits individually connected to said source and to said generator respectively for control thereby, said circuits being adapted and arranged to deliver rectangular wave outputs, two multivibrator circuits each connected to an appropriate one of said wave shaping circuits for individual control thereby, each multivibrator circuit being operative as a frequency divider and the normal output frequencies of the two multivibrator circuits being harmonically related, rotatable means for making a luminous indication, said means including a gaseous discharge tube, means for causing said tube to be periodically excited by output pulses from one of said multivibrator circuits, and means synchronized by output energy from the other of said multivibrator circuits for causing the rotation velocity of said gaseous discharge tube to produce a stroboscopic effect.

14. The combination according to claim 13 and including an electronic limiter stage in each of said wave shaping circuits.

ALFRED KAHN.
